UNITED STATES PATENT OFFICE.

GUSTAF A. BERG, OF CHICAGO, ILLINOIS.

COTTER-PIN PULLER.

1,302,287.

Specification of Letters Patent. Patented Apr. 29, 1919.

Application filed June 30, 1915. Serial No. 37,169.

To all whom it may concern:

Be it known that I, GUSTAF A. BERG, a citizen of the United States, and a resident of Chicago, in the county of Cook and State 5 of Illinois, have invented certain new and useful Improvements in Cotter-Pin Pullers; and I do hereby declare that the following is a full, clear, and exact description thereof, reference being had to the accompanying 10 drawings, and to the characters of reference marked thereon, which form a part of this specification.

This invention relates to a novel tool designed more especially for removing cotter pins from their seats in various kinds of machinery, and also adapted to spread the members of the cotter pin after it has been inserted in its seat.

The object of the invention is to provide 15 an exceedingly simple tool for this purpose which may be produced at small cost and which is light to handle.

A further object of the invention is to provide a tool for this purpose which may be used in "close work" or work where the cotter pin or other part to be manipulated lies very closely adjacent to the surrounding parts of the machine or device so as to preclude the use of pliers or like devices for 20 pulling or prying the cotter pin out of place.

A further object of the invention is to provide, in a compact and light tool, means for exerting heavy hammer thrusts on the cotter pin or the like.

The invention consists in the combination 25 and arrangement of the parts shown in the drawings and described in the specification.

In the drawings:

Figure 1 is a side elevation of a tool embodying my invention showing the handle in full and dotted lines in two positions which it assumes in its use.

Fig. 2 is a cross section through the hammer and shank of the tool.

Fig. 3 is a fragmentary perspective view illustrating the manner of applying the tool to a cotter pin to remove same.

Fig. 4 is a similar view illustrating the manner of spreading the members of the cotter pin after said pin has been seated.

The tool herein shown embodying my invention embraces an elongated shank 10 provided at one end with a turned over portion

or hook 11 and provided at its other end with a head 12. The said shank may be 55 made of steel or other metal possessing the required strength and durability and the head 12 may be formed on the shank by an up-setting operation or may be separately made and fixed to the shank, as desired. 60

14 designates a handle which is slideable on the shank 10 between the hooked end 11 and the head 12. Said handle preferably has the form of an elongated tubular hand piece, with the axial opening 15 thereof of a size 65 to fit loosely over the shank, so that it may slip easily thereover in the direction of the axis of the shank. The hand piece may be grooved or otherwise roughened to enable it to be manipulated by the hand without slipping. It may be made of cast or malleable iron or other material of suitable weight and hardness to act as a hammer.

The said handle is fitted to the shank so as to be non-rotative thereon whereby the 75 pointed end of the tool may be directed to the work by grasping the hand piece, the shank being capable of being turned with the handle by reason of the non-rotative engagement of the handle therewith. As herein shown this non-rotative engagement of the handle with the shank consists in making the shank polygonal in cross section (square as herein shown) and by making the axial opening of the handle of like cross section 80 and, as before stated, of somewhat larger diameter than the external diameter of the shank. Obviously such non-rotative engagement between the handle and shank may be effected in various ways as, for instance, by 85 means of a key and key way or by flattening a round or oval shank and correspondingly forming the opening in the handle.

The turned over or hooked portion 11 of the tool is preferably arranged at an angle 95 to the shank slightly less than a right angle. It is drawn to a point at the free end thereof and is enlarged as it approaches the shank so as to make it generally conical, as herein shown, toward its point of connection with the shank proper. The purpose of sharpening the hook 11 is to enable the tool to be used with cotter pins having eyes of varying diameters and also to produce a rigid hook having ample strength to withdraw larger cotter pins. By reason of the 100

fact that the handle is non-rotatively engaged with the shank of the tool the cotter pin, after being engaged by the hook may be turned in its seat to facilitate the withdrawal of said pin. In forming the hook the end of the shank may be pointed by a suitably shaped tool. Thereafter the handle is slipped over the shank and finally the hook is turned down to the position shown in Fig. 1, as for instance, by the aid of a suitable bending die.

The operation of the tool to withdraw a cotter pin is illustrated in Fig. 3. When the hooked end of the tool is engaged with the eye of the cotter pin the handle is shifted toward the cotter pin and thereafter is forced against the head 12 so as to produce a hammer thrust on the cotter pin to withdraw it from its seat. As before stated, the hammer action of the tool may be supplemented by turning the cotter pin in its seat to close the separated or spread members of the pin to permit the pin to be withdrawn from the opening in which it is seated.

By reason of the fact that the entire tool may be directed by the hand which grasps the handle, the operation of withdrawing the cotter pin may be readily effected by a single hand of the person using the tool.

By reason of the further fact that the advance or hooked end of the tool is small, said tool may be inserted into places difficult of access to tools heretofore used in withdrawing cotter pins and like devices.

In Fig. 4 is shown the manner in which the members of the cotter pin may be opened after the pin has been inserted into its seat. This opening operation is facilitated, as will be obvious, by sharply pointing the end of the hook, whereby it may be readily inserted between the members of the pin to spread them.

It will be understood that the invention is capable of some variations from the illustrated embodiment shown and described

within the spirit of the claims hereto appended.

I claim as my invention:

1. A cotter pin extractor comprising a rod member having a hook formed at one end for engagement with the eye of a cotter pin and having an abutment formed at the other end, and an impact member through which the rod member passes and which is movable longitudinally from said abutment to the hooked end, whereby a cotter pin may be inserted by successive impacts upon its head or withdrawn by successive impacts against the abutment.

2. A cotter pin puller and spreader comprising an elongated shank provided at one end with a head and at its other end with a hook and a member having an opening to loosely and non-rotatively fit over said shank to constitute a hammer to exert percussive force on the head to effect the withdrawal of a cotter pin, and to also constitute a hand piece to direct the tool and to rotate the shank and hook.

3. A cotter pin puller and spreader comprising an elongated shank provided at one end with a head and at its other end with a hook and a member having an opening to loosely and non-rotatively fit over said shank to constitute a hammer to exert percussive force on the head to effect the withdrawal of a cotter pin, and to also constitute a hand piece to direct the tool and to rotate the shank and hook, said hook being disposed at an acute angle to the shank and being pointed at its end and gradually enlarged toward its junction with the shank.

In testimony that I claim the foregoing as my invention I affix my signature in the presence of two witnesses, this 25th day of June, A. D. 1915.

GUSTAF A. BERG.
